STORM WINDOW

Le Roy B. Bachelder, Dayton, Ohio

Application November 26, 1945, Serial No. 630,796

2 Claims. (Cl. 20—55)

1

This invention pertains to building structures, and more particularly to window closures or supplemental weather sash, generally known as "storm" sash, which are adapted to be temporarily installed for winter use and subsequently removed in the spring, or interchanged for summer screen sash.

The object of the invention is to improve the construction as well as the means and mode of installation of such windows, whereby they may not only be economically manufactured and easily installed and removed, but will be more efficient in use, moisture and air tight, of sturdy construction and not likely to get out of repair.

A further object of the invention is to provide air and moisture tight joints for such temporary supplemental sash which will not become swollen when wet and so tightly locked in position as to resist removal.

A further object of the invention is to provide improved attachment means for securing the removable sash in place, and to provide an improved form of ventilator therefor.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

Referring to the drawings, wherein is illustrated the preferred but obviously not necessarily the only form of embodiment of the invention,

Fig. 1 is a rear elevation of an assembled winter or storm sash embodying the present invention, including the permanent or master frame and the removable sash which is interchangeable with a summer screen sash.

Fig. 2 is a vertical sectional view, partly broken away, on line 2—2 of Fig. 1.

Fig. 3 is a horizontal sectional view on line 3—3 of Fig. 1.

Fig. 4 is a detail end and side view of a screw socket or bushing to be embedded in the mounting frame for engagement of an attachment screw.

Fig. 5 is an elevation of an adjustable ventilator slide.

Like parts are indicated by similar characters of reference throughout the several views.

The present supplemental or "storm" sash is intended to be temporarily installed outside a conventional window with its transparent glass panes in parallel spaced relation with those of

the permanent window. The "storm" sash comprises an outer master frame 1, which is fitted to and permanently installed in the window opening, where during summer it may receive and support a screen sash of like construction in alternation with the glazed removable "storm" sash sections 2 and 3.

To afford moisture and air tight joints which will be easily releasable, the vertical side and horizontal bottom rails of the permanently installed master sash 1 are formed with double spaced beveled contact faces 5 and 6, between which is a flat land or face 7 parallel with the general plane of the sash. At its top the master sash 1 is provided with a horizontal top rail 8, having a groove 9 in its lower margin to receive a matching tongue 10 upon the top margin of the upper removable sash section 2. This tongue and groove joint is preferably, but not necessarily, of semi-circular cross section. A similar semi-circular horizontal tongue and groove joint 11 is provided between the upper and lower removable sash sections 2 and 3. The side margins of both the upper and lower removable sash sections 2 and 3 and the bottom rail of the lower section 3 are provided with double bevel contact surfaces 5' and 6' with an intermediate flat face 7' matching the corresponding contact faces of the master frame 1. The intermediate flat faces 7 and 7' of the sash sections 2 and 3 and the frame 1 are normally spaced slightly apart to afford ample clearance space 7" to enable the beveled faces to be drawn more tightly together in wedging engagement. This assures moisture and air tight engagement of the matching beveled faces 5—5 and 6—6, yet enables the sash sections immediately releasable. These pairs of contacting beveled faces being relatively offset with the intervening spaced faces 7—7 therebetween affords ample baffle to intercept any air currents which might leak through the outermost beveled joint.

These joints being beveled, the removable sash are not likely to swell and stick within the bevels of the permanent master frame 1. Hence, the sash sections 2 and 3 are readily removable under whatever conditions may prevail. To hold the sash sections 2 and 3 in their adjusted relation with the permanent or master frame, attachment screws 12 are provided at relatively spaced intervals. To prevent mutilation of the master frame by repetitious insertion and removal of wood screws, internally screw threaded bushings 13 are embedded in the frame 1 at the selected positions 55 for the attachment screws. Such anchor bush-

ings 13 comprise peripherally corrugated bodies having screw threaded bores in which conventional machine screws 12 are engageable. The exterior corrugations 14 of the anchor inserts 13 may be disposed either helical or parallel, and are preferably beveled so that they may be more easily driven into preformed holes in the master frame 1, but will resist displacement therefrom. The corrugated peripheries of the anchor bushings are further provided with longitudinal splines 15 into which the wood frame expands to lock the inserts against rotation. To further secure the anchor inserts 13 against displacement, one or more brads or nails 16 may be driven diagonally into the master frame into thrust engagement with the corrugations of the inserts 13.

To afford temporary ventilation the master frame 1 is provided with an opening 17 at any convenient point, which is exteriorly overlaid by a closure slide 18 having therein a large opening or a group of small openings 19 which may be brought into registry with the sash frame opening 17 to admit air. The ventilating opening 17 may be closed by shifting the slide 18. The slide closure is provided with angular slots 19, through which extend guide screws 20, relative to which the closure slide may be elevated in an upwardly diagonal direction and then permitted to descend by gravity in an opposite diagonal direction, where it is held by gravity in alternately open and closed positions.

It is to be understood that the present window sash is designed to be removed from its mounting into the interior of the building structure. Wherefore, Fig. 1 is an elevational view of the inner side of the assembly and from the left of Fig. 2.

The marginal rabbet 1a of the master frame 1, as shown on the top and side frame members in Fig. 1, is adapted to fit within and slightly overlap the margin of the top and sides of the original window frame of a wooden structure or the corresponding parts forming the window opening of a brick, stucco, or concrete structure. While, as before mentioned, the sash members 2 and 3, whether of the storm variety or summer screens, are preferably removable inwardly from the master frame or mount 1, the assembly may be removed toward the exterior without departure from the principle involved or the scope of the invention.

While throughout the specification and in the following claims reference is made to the assembly as a "window" closure and "window" sash, it is to be understood that the invention is not restricted thereto, but is equally applicable to door openings wherein the assembly forming the subject matter hereof may be utilized as a convertible storm door for winter use and a screen door for summer use. Consequently, the terms "window structure" and "storm window" and "storm sash" herein employed shall be interpreted generically to include also doors of both storm and screen type within the scope of the accompanying claims.

From the above description it will be apparent that there is thus provided a device of the character described possessing the particular features of advantage before enumerated as desirable, but which obviously is susceptible of modification in its form, proportions, detail construction and arrangement of parts without departing from the

principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

15. 1. A supplemental temporary "storm" window, wherein a master frame is permanently secured in a window opening in parallel spaced relation with the normal window sash thereof, with which upper and lower sash sections are 20 detachably engageable, characterized by horizontal tongue and groove joints between the detachable upper and lower sash sections, and between the upper sash section and the top rail of the master frame, double beveled joints between 25 the vertical side margins and bottom margin of the lowermost of the detachable sashes and the interior vertical side and bottom margins of the permanently mounted master sash, comprising parallel laterally offset beveled contact faces on 30 the respective sashes and frame and flat parallel faces intermediate the beveled contact faces of the frame and respective sashes in parallel relatively spaced relation with each other, affording intermediate clearance for wedging adjustment 35 of the opposed beveled contact faces, machine screws for attaching the detachable sashes to the master sash, and anchor inserts having screw threaded bores embedded in the master sash receiving the ends of the machine screws when 40 thrust through the removable sash.

2. A window structure wherein a divided sash member is detachably engageable with a supporting frame, including substantially semi-circular tongue and groove joints between the 45 visible sections of the sash member and between the top of the divisible sash member and the top of the frame, and beveled interengaging marginal contact faces between the vertical sides and bottom of the sash and frame, and pressure 50 means for drawing the sash into tight wedging engagement of the beveled contact faces of the sash with those of the frame.
